US0D1084258S

(12) **United States Design Patent** (10) Patent No.: **US D1,084,258 S**
(45) Date of Patent: ** Jul. 15, 2025

(54) **INLET/OUTLET CONNECTOR FOR HEAT EXCHANGER**

(71) Applicant: **Danfoss A/S**, Nordborg (DK)

(72) Inventors: **Zhifeng Zhang**, Zhejiang (CN); **Jun Luo**, Zhejiang (CN); **Qin Xu**, Zhejiang (CN)

(73) Assignee: **DANFOSS A/S**, Nordborg (DK)

(**) Term: **15 Years**

(21) Appl. No.: **29/771,045**

(22) Filed: **Feb. 19, 2021**

(30) **Foreign Application Priority Data**

Aug. 21, 2020 (CN) 202030483373.5

(51) LOC (15) Cl. **23-03**

(52) U.S. Cl.

USPC **D23/323**; D23/259

(58) **Field of Classification Search**

USPC D23/322, 323, 259, 262

CPC F28D 9/005; F28D 9/0043

See application file for complete search history.

(57) **CLAIM**

The ornamental design for an inlet/outlet connector for heat exchanger as shown and described.

DESCRIPTION

The patent or application file contains at least one drawing executed in color. Copies of this patent or patent application publication with color drawing(s) will be provided by the Office upon request and payment of the necessary fee.

FIG. 1 is a bottom view of an inlet/outlet connector for heat exchanger in accordance with a first embodiment comprising a new, original and ornamental design;

FIG. 2 is a front view thereof;

FIG. 3 is a front and top perspective view thereof;

FIG. 4 is a top thereof;

FIG. 5 is a front view of the inlet/outlet connector for heat exchanger in accordance with a second embodiment;

FIG. 6 is a front and top perspective view thereof;

FIG. 7 is a top view thereof; and,

FIG. 8 is a bottom view thereof.

**1 Claim, 8 Drawing Sheets
